Delaware

Application August 26, 1947, Serial No. 770,637

15 Claims. (Cl. 315—6)

1

The present invention relates to the art of electron-discharge devices and particularly relates to electron-discharge devices of the velocity-modulation type.

One form of a velocity-modulation electron-discharge device is a klystron. In a klystron, bunching is usually accomplished by exciting a single resonant circuit with a voltage of substantially sinusoidal waveform.

The efficiency of a klystron is increased by causing all the electrons passing the resonant circuit of the catcher during each cycle to reach the resonant circuit of the catcher at substantially the same instant. It can be shown as follows that this result may be attained by utilizing a bunching voltage having a periodic sawtooth waveform. A voltage excursion of sawtooth waveform, having a period of 2π , may be defined by the equation

$$V = \frac{1}{2}V_1T(-\pi < T < \pi) \quad (1)$$

where T represents the time phase at which an electron passes the center of the bunching space and V_1 is a constant.

If θ is the corresponding time phase quantity at the catcher, normalized to vanish when T vanishes, then for a peak alternating voltage V_1 across the buncher resonator grids (assumed small in relation to the beam voltage V_0), θ is given by

$$\theta = T\left(1 - \frac{r}{2}\right)$$

where

$$r = \left(\frac{WL}{2v_0}\right)\left(\frac{V_1}{V_0}\right) = \pi N \frac{V_1}{V_0}$$

in which

 W =Input radian frequency, L =Length of drift space between buncher and catcher resonators, v_0 =Average electron velocity in drift space, and N =Drift time measured in cycles of the voltage V_1 .

A periodical representation of the voltage excursion defined by Fig. 1 is indicated by the Fourier series

$$V = V_1[\sin T - \frac{1}{2} \sin 2T + \frac{1}{3} \sin 3T \dots] \quad (3)$$

Thus

$$\theta = T - r(\sin T - \frac{1}{2} \sin 2T + \dots) \quad (4)$$

Consideration of only the first three terms of Equation 4 and generalization of its first two sine terms leads to

$$\theta_1 = T - X \sin T + Y \sin 2T \quad (5)$$

10 θ_1 is substantially constant during each cycle and all electrons passing the buncher during a cycle reach the catcher at approximately the same instant. Under these conditions the efficiency of the klystron is maximum. According to the present invention, an approximation to the desirable sawtooth bunching voltage waveform is provided in a very simple manner, as will appear hereinbelow.

Accordingly it is an object of the present invention to provide a more efficient klystron device.

15 It is a further object of the present invention to provide apparatus for producing, in a velocity-modulation electron-discharge device, a bunching voltage approximating a non-sinusoidal waveform.

It is a still further object of the present invention for providing a simple klystron utilizing a bunching voltage of approximately sawtooth waveform.

It is yet another object of the present invention to provide a novel multi-resonator electron-discharge device.

20 Calculations with Equation 4 show that, for a klystron frequency multiplier, in which the natural resonant frequency of the catcher resonator is substantially four times that of the buncher resonator, the efficiency factor F_4 attains its maximum value at $X=1.68$ and $Y=0.45$ and provides a definite improvement over the maximum efficiency factor of a klystron multiplier utilizing a sinusoidal bunching voltage. The efficiency factor F_m (where m is the order of the harmonic to which the catcher resonator is tuned) for large values of m , attains its maximum value in the neighborhood of $X=4/3$ and $Y=1/6$ and greatly exceeds the maximum efficiency factor of the corresponding klystron multiplier utilizing a sinusoidal bunching-voltage waveform. According to the present invention, an approximation of the bunching voltage waveform required to cause the constants in Equation 5 to attain these values is provided in a very simple manner.

25 Accordingly it is yet a further object of the present invention to provide a klystron frequency multiplier of greatly increased efficiency.

30 In accordance with one aspect of this invention, these objects are attained by providing an improved composite buncher in place of the conventional simple buncher resonator. Such a composite buncher is formed of a first or input cavity resonator tuned to the input frequency, in combination with a second floating resonator

tuned in the neighborhood of a harmonic which is preferably twice the input frequency, these two resonators being separated by a drift-space-defining member. The catcher or output resonator is then located spaced from the floating resonator by a second drift-space. As herein used, the term "floating resonator" may be defined as a resonator which does not have any source of energy external to the klystron and which is not coupled to a load utilizing the output of the resonator; however a circuit element may be coupled to the floating resonator, solely for affecting some electrical characteristic of the floating resonator. It is positioned at a point intermediate the input and output resonators at which the electron beam is as yet underbunched, that is, in a condition in which the electron beam has not yet attained the full density-modulated condition necessary for energy-extraction therefrom. The floating resonator is excited into oscillation solely by the underbunched beam, and reacts on the beam to velocity-modulate it at the second harmonic frequency. The combination of buncher resonator, drift space and floating resonator may be properly termed a composite buncher since it acts substantially like a single bunching resonator to produce the desired non-sinusoidal-bunching voltage waveform.

For a klystron amplifier, the catcher resonator is made to have substantially the same natural resonant frequency as the first resonator. For a klystron multiplier, the catcher resonator is made to have a natural resonant frequency substantially m times that of the first resonator, where m is the order of the desired harmonic.

The invention also relates to the novel features or principles of the instrumentalities described herein, whether or not such are used for the stated objects, or in the stated fields or combinations.

Fig. 1 is a schematic diagram of an improved form of klystron amplifier in accordance with the teachings herein.

Fig. 2 is a similar schematic diagram of an improved form of klystron frequency multiplier according to the present invention.

Referring to Fig. 1, the klystron amplifier shown therein includes a cathode 2 and a reentrant buncher resonator 3 having a pair of electron-permeable walls or grids 4 and 5 aligned with cathode 2. Beyond buncher resonator 3 is located a reentrant floating resonator 6 spaced from buncher resonator 3 by a drift tube 7 of length L_1 and having a pair of electron-permeable walls or grids 8 and 9 also aligned with cathode 2. Floating resonator 6 has a natural resonant frequency substantially twice that of buncher resonator 3. Beyond floating resonator 6 is a reentrant catcher resonator 10 spaced from floating resonator 6 by a drift tube 11 of length L_2 and having a pair of electron-permeable walls or grids 12 and 13 also aligned with cathode 2. Catcher resonator 10 is designed to have a natural resonant frequency substantially the same as that of buncher resonator 3. An input coaxial line terminal or coupling 14 is provided in buncher resonator 3 for supplying input energy to buncher resonator 3, and an output coaxial line terminal or coupling 15 is provided for obtaining energy from catcher resonator 10. For operation of the amplifier as an oscillator or regenerative amplifier, a feedback loop may be connected between input coaxial line terminal 14 of buncher resonator 3 and a second coaxial line

terminal 15' provided in catcher resonator 10. A similar coaxial line terminal 14' is provided for floating resonator 6, to which an impedance element may be connected for controlling or changing some characteristic of the floating resonator 6, such as its shunt impedance, Q , resonant frequency, or to adjust the gain between the input and floating resonators.

Beyond catcher resonator 10 is positioned a collector plate or electrode 19 for collecting the electrons after their traversal of the resonators. This collector electrode may be formed as a wall of the device provided this wall is electrically insulated from cathode 2.

Respective tuning rods 16, 17 and 18 are provided for resonators 3, 6 and 10 for independently adjusting or tuning these resonators. Any other tuning means or resonator structure permitting tuning may be employed, if desired.

In operation, the electron beam from cathode 2 traverses buncher resonator 3 where it is velocity-modulated by the electromagnetic field therein which produces an alternating electric field between electron-permeable walls 4 and 5. The velocity-modulated beam is partially bunched in the drift tube 7 and then traverses the floating resonator. Inasmuch as components of both the frequency of excitation of buncher resonator 3 and harmonics thereof are present in the electron beam, floating resonator 6 is excited into oscillation at the second harmonic to which it is tuned. The oscillating field within the floating resonator 6 will in turn react on the electron beam to velocity-modulate the electron beam at this second harmonic.

After the electron beam traverses the floating resonator 6, the bunching of the beam is completed in the drift tube 11 beyond the floating resonator 6. The bunched electron beam then traverses the catcher resonator 10 to give up energy to the oscillating electromagnetic field within the catcher resonator 10. The load to be excited by the amplified energy is coupled to the output coaxial line terminal 15 provided in catcher resonator 10.

The input resonator 3, the drift tube 7 and the floating resonator 6 form the composite buncher of the present invention. Despite the fact that both resonators 3 and 6 are excited by sinusoidal oscillations, their net effect is to velocity modulate the electron beam between cathode 2 and collector 19 in the same manner as the electron beam would be modulated if it were acted upon by a buncher excited by a periodic voltage of sawtooth waveform. Thus a practical approximation to the desired sawtooth waveform for the buncher voltage is obtained, and as a result, when the circuit parameters are properly proportioned, the bunched electrons may be caused to traverse the catcher according to the relationship shown in Equation 5. The values for X and Y of Equation 5 are obtained by suitable selection or adjustment of the gain between input resonator 3 and floating resonator 6, and of the resonant frequency of resonator 6. As stated above, maximum efficiency for the klystron amplifier is obtained in the neighborhood of $x=2$ and $y=1$, and has been found to be much greater than the maximum efficiency of the two-resonator klystron amplifier shown in Fig. 1 of U. S. Letters Patent No. 2,242,275 to R. H. Varian, and also to be greater than the maximum efficiency of a three-resonator cascade amplifier of the type shown in Fig. 1 of U. S. Letters Patent No. 2,280,824 to W. W. Hansen et al., in which a floating resonator is pro-

vided having the same natural resonant frequency as the other two resonators. The considerations leading to the proper selection of parameters will become clearer from the following discussion, for which it is necessary to define certain quantities, as follows:

N_1 =Average transit time in cycles between input and floating resonator.

N_2 =Average transit time in cycles between floating and catcher resonators.

Thus N_1 and N_2 are proportional to L_1 and L_2 .

$$B = \tan^{-1} \left[2Q_2 \frac{w-w_2}{w_2} \right]$$

where B is the phase angle between the high frequency component of beam current and the high frequency voltage at the floating resonator and is varied by tuning the floating resonator, Q_2 is the Q of the floating resonator, W is the frequency in radians to which resonator 3 is tuned and W_2 is the frequency in radians to which the floating resonator is tuned.

F_m =efficiency factor, defined as

$$\overline{\exp. jm\theta}$$

where m is the order of the harmonic to which the catcher is tuned and the overline indicates an average over a full cycle of values of T .

G_0 =the ratio of the floating resonator normalized alternating voltage a_2 to the normalized alternating buncher voltage a_1 for $B=0$.

Hence

$$G_0 = a_2/a_1 = \pi \frac{N_1 N_2}{N_1 + N_2} \frac{R_{2s}}{R_0}$$

where $a_1=V_1/V_0$, $a_2=V_2/V_0$, V_2 is alternating voltage across the floating resonator grids, R_{2s} is the shunt impedance of floating resonator and R_0 is the beam impedance which is equal to beam voltage V_0 divided by cathode current I_0 .

The following table shows the relation between these parameters.

[f or the optimum condition of $X=2$, $Y=1$.]

N_2/N_1	G_0	B	F_1
Degrees			
.25	8.4	15.0	.763
.50	5.3	27.5	.759
1.00	3.5	34.0	.750
2.00	2.8	46.0	.748
4.00	2.6	55.0	.752

A ratio N_2/N_1 of 3.70 has been found to yield highly desirable results. Since the length of drift tubes 7 and 11 are directly proportional to N_1 and N_2 respectively, it follows that tube 11 should be from 3 to 4 times as long as tube 7 for optimum results.

It will be observed that all values of the phase angle B for the conditions of operation listed in the table above are positive indicating that the high frequency voltage at the floating resonator leads the high frequency component of beam current which passes through the resonator. In order to attain this condition in operation, the floating resonator 6 of the apparatus disclosed in Fig. 1 must be tuned to a frequency slightly greater than twice the resonant frequency of resonator 3.

These values of F_1 may be compared with the peak value .58 for the conventional two-resonator klystron amplifier, leading to an increase in theoretical power output of approximately 70% for the present device.

In each case, the optimum tuning of the floating resonator is a function of G_0 . However, near $N_2/N_1=0.5$, F_1 is practically independent of G_0 for G_0 greater than 4.

5 The circuit parameters indicated in Fig. 1 may be proportioned so that the on-resonance gain G_0 when $B=0$ is the exact value desired, or the circuit parameters may be proportioned so that the gain G_0 is larger than the value desired and 10 then the shunt impedance R_{2s} of the floating resonators may be reduced by coupling a resistor to the coupling 14' of the floating resonator. Desirably, a non-linear resistor, such as a germanium or silicon crystal or a thermistor may be 15 used, so that the gain can be controlled as a function of the amplitude of oscillation, to keep the apparatus near optimum operating condition.

Fig. 2 is a schematic diagram of improved frequency multiplier using the principles of the present invention. The frequency multiplier of Fig. 2 includes a cathode 22 and a reentrant buncher resonator 23 of resonant frequency f and having a pair of electron-permeable walls or grids 24 and 25 aligned with cathode 22. Beyond buncher 25 resonator 23 is floating resonator 26 spaced from buncher resonator 23 by drift tube 27 and having a pair of electron-permeable walls or grids 28 and 29 also aligned with cathode 22. The natural resonant frequency of floating resonator 26 is 30 made substantially twice that of the buncher resonator 23. Beyond floating resonator 26 is catcher resonator 30 spaced from floating resonator 26 by drift tube 31 and having a pair of opposing electron-permeable walls or grids 32 and 33 aligned with cathode 22. It has a natural resonant frequency mf which may be the fourth or larger order harmonic of the natural resonant frequency f of the buncher resonator 23.

Beyond catcher resonator 30 there is provided 40 an electron collector plate 39. Respective input and output coaxial line terminals 34 and 35 are provided in buncher resonator 23 and output resonator 30. Tuning rods 36, 37 and 38 are respectively provided in buncher, floating and catcher 45 resonators 23, 26 and 30 for individually tuning the resonators. As in the apparatus of Fig. 1, there is provided in floating resonator 26 a coaxial line terminal 40 to which an impedance element may be connected for controlling or changing some characteristic of the floating resonator 26.

In operation, energy of frequency f is fed into 55 buncher resonator 23 by means of input coupling loop 34. The electron beam from cathode 22 is velocity-modulated by the alternating field within buncher resonator 23 and is only partially bunched in the drift tube 27. The underbunched electron beam, in traversing floating resonator 26, excites it into oscillation at the second harmonic 60 $2f$, which oscillations in turn react on the electron beam to velocity-modulate it at the second harmonic. Optimum bunching of the electron beam is effected in the drift tube 31 and the desired output harmonic is extracted from the electron beam by the catcher resonator 30. The electron beam after traversing catcher resonator 30 impinges upon and is collected by the collector plate 39 beyond the catcher resonator 30. As in 65 the apparatus of Fig. 1 that portion of the apparatus of Fig. 2 including the buncher resonator 23, drift tube 27 and floating resonator 26 may be termed the "composite buncher," and produces the advantages of the present invention. 70 By suitable gain and resonator tuning adjustments, the composite buncher can be adjusted

to impart desired amounts of first and second harmonic velocity-modulation to the beam.

The proper adjustment of the device of Fig. 2 is indicated by the following table, similar to that set out above, for the optimum condition of

[$X=1.68$, $Y=0.45$.]

N_2/N_1	G_0	B	F_4
Degrees			
0.25	6.38	-27.5	.610
0.50	3.48	-5.5	.607
1.00	2.35	11.5	.600
2.00	1.90	29.0	.584
4.00	2.05	44.5	.583

Here again, where G_0 is too high, it may be reduced as discussed relative to the amplifier of Fig. 1.

In general, in Fig. 2 as in Fig. 1, the floating resonator should not be tuned exactly to the second harmonic, but should be detuned therefrom as indicated by the value of B in the above tables. The values of the phase angle B for the conditions of operation listed above indicate that for N_2/N_1 ratios of 0.25 and 0.50 the floating resonator 26 must be tuned to a frequency slightly less than twice the resonant frequency of resonator 23, and for N_2/N_1 ratios of 1.00 and larger the floating resonator must be tuned to a frequency slightly greater than twice the resonant frequency of resonator 23.

The maximum obtainable efficiency of the frequency multiplier of Fig. 2 has been found to be much greater than the maximum obtainable efficiency of the two resonator klystron multiplier utilizing a sinusoidal bunching voltage.

Although only the first and second harmonic terms of the Fourier expansion of Equation 4 were used in determining the number of resonators in the composite bunchers of Figs. 1 and 2, the invention is not restricted only to those two terms. More than two terms may be used, resulting in a corresponding increase in the number of resonators of progressively increasing harmonic order forming the composite buncher. Also, although in the apparatus of Figs. 1 and 2 the first and second terms of the Fourier expansion of Equation 4 were used for the two resonator composite buncher, the two terms used may be the first and any other harmonic, and the frequencies of the first and second resonators of the two resonators of the composite buncher would then be the fundamental and the other harmonic respectively. However these modifications do not realize all the advantages of the invention.

Thus, by the provision in velocity-modulated amplifiers and multipliers of novel bunching apparatus capable of producing a desired non-sinusoidal affective bunching-voltage waveform, more efficient velocity-modulation electron-discharge devices are produced.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. An ultra-high-frequency electron-discharge device comprising means for producing an electron beam including a cathode; a cavity resonator having a predetermined natural reso-

nant frequency and having a pair of electron-permeable walls aligned with said cathode; first means defining an electron drift space beyond said first cavity resonator; a second and floating cavity resonator beyond said first electron-drift-space-defining means and having a natural resonant frequency substantially twice that of said first cavity resonator, said second cavity resonator having a pair of electron-permeable walls aligned with said cathode, the drift space between the electron-permeable walls of said first and second resonators being substantially less than the space required to cause the electron beam to attain maximum density modulation; second means beyond said second cavity resonator defining a further electron drift space; and means beyond said second electron-drift-space-defining means for extracting energy of frequency other than that of the second cavity resonator from said electron beam.

2. Apparatus as in claim 1 wherein said energy-extracting means is a cavity resonator having a natural resonant frequency other than that of said second cavity resonator.

3. Apparatus as in claim 1 in which said energy-extracting means is a cavity resonator having a natural resonant frequency substantially the same as that of the first cavity resonator.

4. Apparatus as in claim 1 in which said energy-extracting means is a cavity resonator having a natural resonant frequency harmonically related to that of said first cavity resonator and greater than the frequency of said second resonator.

5. Ultra-high-frequency velocity-modulation apparatus comprising a cathode, a first resonator having a predetermined natural resonant frequency and having an electron-permeable portion aligned with said cathode, first means defining an electron drift space beyond said first cavity resonator; a second resonator beyond said first drift space and having a predetermined natural resonant frequency substantially twice that of said first resonator, said second resonator having an electron-permeable portion aligned with said cathode, the drift space between the electron-permeable portions of said first and second resonators being less than the space required to cause the electron beam to attain substantially maximum density modulation, second means defining an electron drift space beyond said second resonator, and an energy-extracting circuit beyond said second drift space for extracting energy from the electrons of a frequency different from the natural resonant frequency of said second resonator.

6. Apparatus as in claim 5 in which said energy-extracting circuit is a cavity resonator having a natural resonant frequency substantially the same as that of said first resonator.

7. Apparatus as in claim 5 in which said energy-extracting circuit is a cavity resonator having a natural resonant frequency harmonically related to that of the first resonator and greater than that of the second resonator.

8. A composite buncher for electron discharge devices of the velocity modulation type having means for producing an electron stream, comprising a first cavity resonator along the path of said stream for velocity modulating said electron stream, a second floating resonator along said path beyond said member and tuned to substantially twice the resonant frequency of said first resonator, and a drift tube member 75 surrounding said path between said first and

second resonators, said drift tube member having a length substantially less than the length required to cause said velocity-modulated electron stream to attain maximum density modulation.

9. A composite buncher as in claim 8 in combination with further cavity resonator means along said stream path for extracting energy from said stream at a desired output frequency different from that of said second resonator.

10. An ultra-high-frequency electron discharge device comprising means for producing an electron stream along a predetermined path, resonant means along said path for producing velocity modulation of the electrons of said stream, second resonant means spaced from said first resonant means and located at a point where said stream is in under-bunched condition for further velocity modulating said stream, said second resonant means being tuned to a frequency substantially twice the resonant frequency of said first resonant means, and resonant energy-extracting means spaced along said stream path from said second resonant means by a distance substantially three times the spacing between said first and second resonant means.

11. Apparatus as in claim 10, wherein each of said resonant means is a cavity resonator positioned in energy-exchanging relation to said stream.

12. Apparatus as in claim 11, wherein said second resonant means is tuned to a frequency greater than twice the resonant frequency of said first resonant means, and differing therefrom by an amount less than the band-width of said second resonant means, whereby the oscillating field of said second resonant means is phase-shifted relative to the corresponding current component of the electron stream coupled thereto.

13. A composite buncher for electron-discharge devices of the velocity-modulation type having means for producing an electron stream, comprising first resonant means along the path of said stream for producing velocity modulation of said stream, a drift tube member surrounding path beyond said first said resonant means, and a second resonant means along said path beyond said member at a point where said stream is in under-bunched condition, said second resonant means being tuned to a frequency greater

than twice the resonant frequency of said first resonant means and differing from said twice frequency by an amount less than the band-width of said second resonant means, whereby said second resonant means is adapted to be excited by said under-bunched stream with a phase differing from the corresponding current component of said stream, whereby the velocity modulation of said stream is enhanced to produce more efficient bunching of the electrons of said stream beyond said second resonant means.

14. An electron discharge device comprising means for producing an electron stream along a predetermined path, a first cavity resonator 15 along said path and having a predetermined resonant frequency, a second floating cavity resonator positioned along said stream path beyond said first resonator and tuned to a natural resonant frequency substantially equal to but slightly greater than twice that of said first resonator, and a third output cavity resonator positioned 20 along said stream path beyond said second resonator and tuned to a frequency different from that of said second resonator for extracting energy of said different frequency from said electron stream.

15. An electron discharge device comprising means for producing an electron stream along a predetermined path, three cavity resonators 30 positioned successively along said path, the intermediate resonator having a resonant frequency substantially twice that of the first resonator, a drift-space-defining member connecting said intermediate and first resonators, and a further drift-space-defining member connecting said intermediate resonator and the third resonator, the drift space defined by said further member being substantially three times that defined by said first member.
